(57) **CLAIM**

The ornamental design for a part of stylus, as shown and described.

DESCRIPTION

FIG. 1 a front perspective view of a part of stylus between a stylus body and a stylus tip showing our new design; FIG. 2 is a close up view of an end of the tip of FIG. 1; FIG. 3 is a left side view thereof; FIG. 4 is a close up view of an end of the tip of FIG. 3; FIG. 5 is a right side view thereof; FIG. 6 is a close up view of an end of the tip of FIG. 5; FIG. 7 is a top view thereof; FIG. 8 is a close up view of an end of the tip of FIG. 7; FIG. 9 is a bottom view thereof; FIG. 10 is a close up view of an end of the tip of FIG. 9; FIG. 11 is a rear view thereof; and, FIG. 12 is a front view thereof.

The stippled shading represent the surface of the stylus. The broken lines in the figures show portions of the stylus; the broken lines themselves form no part of the claimed design.

The dot-dash broken lines illustrate boundaries of the claimed design; the dot-dash broken lines themselves form no part of the claimed design.

The thinner solid lines at the end of the stylus tip illustrate a rubber ring between the stylus body and the stylus tip.
